The ornamental design for a palette box, as shown and described.

DESCRIPTION

FIG. 1 is a bottom view of a palette box showing the new design, shown in a closed position of use;

FIG. 2 is a front view thereof;

FIG. 3 is a side view thereof;

FIG. 4 is a perspective view thereof;

FIG. 5 is a back view thereof;

FIG. 6 is a side view thereof;

FIG. 7 is a top view thereof; and,

FIG. 8 is a perspective view thereof, shown in an open position of use.

In the drawings, the broken lines represent portions of the article which form no part of the claimed design.
